UNITED STATES PATENT OFFICE.

LEWIS METESSER, OF NEW ORLEANS, LOUISIANA.

FURNACE.

1,287,602.

Specification of Letters Patent. Patented Dec. 10, 1918.

Application filed August 17, 1916. Serial No. 115,468.

To all whom it may concern:

Be it known that I, LEWIS METESSER, a citizen of the United States, residing at New Orleans, in the parish of Orleans and State of Louisiana, have invented certain new and useful Improvements in Furnaces, of which the following is a specification.

This invention relates to improvements in furnaces and particularly metallurgical furnaces wherein metals or their alloys are heated, melted, puddled, annealed or otherwise treated and the invention also relates to the construction of kilns for nodulizing, vitrifying and the like.

An important object of this invention is to produce a furnace of the character described, in which the degree of heat and the character and extent of chemical action therein can be effectively controlled and both the heat and chemical action maintained substantially uniform throughout the treatment of the material therein.

A further object of the invention is to provide a furnace of increased efficiency and economy of operation.

Other objects and advantages of the invention will be apparent during the course of the following description.

In the accompanying drawing forming a part of this specification and in which like numerals are employed to designate like parts throughout the same,

Figure 1 is a transverse vertical sectional view taken on line 1—1 of Fig. 3 and looking in the direction of the arrows,

Fig. 2 is a similar view taken on line 2—2 of Fig. 3 looking in the direction of the arrows, and,

Fig. 3 is a longitudinal vertical section taken approximately on line 3—3 of Fig. 1.

In the drawings, wherein for the purpose of illustration is shown a preferred embodiment of my invention, the numeral 5 designates the shell or body portion of the furnace, in the forward portion of which is formed a combustion chamber 6, as shown. This combustion chamber may be of any required area and form, and is adapted to receive any suitable mechanically or manually operated mechanism for handling fuel, the same being of adequate capacity for the kind and quality of fuel to be burned. This combustion chamber, in the type of furnace illustrated, is provided in its lower portion with an inclined grate 7, comprising spaced sets

of twy whole 8, which are hollow and have laterally extending outlet openings 9, discharging into the chamber 6, and inlet openings or chambers, as is well known. These twy whole 8 are arranged upon a bed plate 7'. The inlet 60 openings or chambers of the twy whole 8 communicate with a gas supply passage 10, closed at its top and opened at its bottom, as shown.

The fuel, such as coal, coke or the like, is 65 fed into the combustion chamber 6 by means of feeding mechanism 9' which may be of any well known or preferred construction, serving to force the fuel between the sets of twy whole 8, such fuel passing into the combustion chamber 6, wherein it is subjected to the action of heat and of gases discharging from the openings 9 of the twy whole.

Arranged within the lower portion of the shell 5 is an open top, water cooled and 75 water sealed ash pit 12, formed by the walls 13, 14, and 15. The wall 15 may be formed of masonry or metal plates, as may be best suited to the conditions of each case.

The open top water cooled and water 80 sealed ash pit 12 is provided near its bottom with a water seal 15', having an outlet 16, for the mechanical or manual removal of ashes. This outlet may be formed through the front, rear or side walls of the construction. The mechanical cleaning may be accomplished without disturbing the water seal of the ash pit 12. This prevents materially changing the character of combustion or degree of temperature in the combustion 85 chamber 6 or effecting furnace capacity. The partially consumed fuel in the open upper part of the ash pit 12 forms a fire surface for finishing the gasification or complete combustion of the fuel in the fire box 90 and the closed lower part of the receptacle receives the incombustible parts of the fuel, after discharge into the same, by any suitable means, provided for the purpose. The water seal is provided with drain and over-flow pipes or openings 17' and 17", as shown.

Arranged upon the back wall of the combustion chamber 6 is a water back or iron plate 12', behind which are disposed pipes 14' receiving water from means to be described. The provision of the iron plate 12' prevents the adhering of clinkers and the provision of the water cooling pipes 14' preserves the plate as is well understood in the art. The water supplied to pipes 14' passes 110

therethrough and is discharged into the ash pit 16 through pipe 15^a.

The numeral 17 designates a wind box, preferably closed upon all sides and bottom 5 and opened at its top, for free communication with the gas passage.

Arranged near the rear or inner end of the wind box 17 and under the overhanging edge 10 of the bed plate 7', as shown, is a perforated pipe 18, discharging water upon rear end of the wind box to externally cool it. The perforated pipe 18 also serves to supply water into the ash pit, introducing the water beneath the hot incombustible mass, for supplying, by disintegration, oxygen to the rear 15 part of the combustion chamber, to complete the gasification of such parts of combustible material as may be automatically discharged over the open top of the ash pit, and for supplying water to the seal.

The pipe 18 is connected with the pipe 14' by a pipe 20. Water is fed into the pipe 18 through a pipe 21, having a valve 22 connected therein. This pipe has connection 25 with any suitable source of water supply. The pipe 21 has connection with a transverse pipe 23, for the external cooling of the frame of the cleaning door 24.

The combustion chamber 6 has an outlet 30 opening 25, for the passage of gases and products of combustion into the usual heating and treating chamber, containing the metals or ores or the like to be treated. The door 24 leads into the combustion chamber 35 6, near and above the ash-pit 12, whereby access may be had thereto, for cleaning.

The numeral 26 designates an air supply pipe, having branches 27 and 28. Each branch is equipped with a quick acting slide 40 valve 29, for controlling the passage of air therethrough. The branch 28 discharges into the wind box 17, as shown, for the partial gasification or complete combustion of the fuel, and supplying the same air pressure 45 at all times to the twyters. The branch 27 discharges into a preferably vertical air heating passage or conduit 30, formed in the bridge wall 31. The opening 30 extends upwardly and discharges into a horizontal 50 passage 32, formed in such wall, and provided with outlet ports or openings 33 discharging into the ore treating chamber. The function of this construction is to provide preheated air, for secondary combustion, and it is to be understood that such 55 preheated air may be supplied from the heating chamber of any desired form and capacity of preheater required. The discharge of the air through the branches 27 and 28 is 60 regulated by the slide valves 29.

It will be understood that, by the provision of a single air supply pipe 26 and the branches 27 and 28 connected therewith as shown, the air is normally supplied for fuel 35 combustion through the twyters 8 and for sec-

ondary combustion through the preheating conduits 30, at the same pressure and that by manipulation of the valves 29 this pressure may be regulated as desired.

The numeral 34 designates a steam supply 70 pipe, connected with a duplex valve structure 35. This valve structure is connected with a pipe 36 adapted to discharge to the atmosphere. Connected with the valve structure is a pipe 37 discharging into the 75 wind box 17. The valve structure 35 comprises quick acting valves 38 and 39, the valve 38 serving to close the pipe 36 while the valve 39 opens the pipe 37, and vice versa. The valves 38 and 39 are simultaneously operated by a lever 40, pivoted at 41. The duplex valve system consists of two 80 duplicate quick opening valves, with central fitting, which central fitting has two vertical openings to the valves and two horizontal 85 openings for connection with the supply pipe, and fulcrum of lever. The needed pressure for creating the draft which pressure may be steam, exhaust or live, or various gases, or combination of two or more 90 gases is supplied through the duplex valve structure to produce the desired character of combustion and degree of heat, within the limit of the fuel used, and chemical mixtures within the combustion chamber, to perform the required work, such as heating metals for rolling, forging, and other forms of fabrication, melting, converting, and annealing, carbonizing or roasting ores in furnaces, and nodulizing and vitrifying in kilns 95 various combination and products.

In the operation of the valve system shown, steam or other chemical gases enter the supply pipe, and pass down through valve 39, when lever 40 is out, into the wind 105 box 17, or up through valve 38 to the atmosphere or waste, when the lever is in reverse position. One movement of lever simultaneously operates both valves 38 and 39. The pipe 34 and associated elements are provided to utilize the exhaust steam from an engine, by supplying the same to the furnace without substantially impairing the operation of the engine. If the exhaust from the engine is substantially retarded, 110 the operation of such engine is seriously impaired. A single valve to alternately place one branch pipe into and out of communication with and from the steam supply pipe could not be operated sufficiently quickly, to prevent substantial back pressure in the engine. It is essential that there be two valves 115 38 and 39, which are simultaneously set into action, one closing and one opening, so that their operation is simultaneously completed. 120

It is to be understood that the form of my invention herewith shown and described is to be taken as a preferred example of the same, and that various changes in the shape, size, and arrangement of parts may be re- 130

sorted to without departing from the spirit of the invention or the scope of the subjoined claims.

Having thus described my invention, I

5 claim:

1. In a furnace of the character described, a shell having therein a combustion chamber, an open top water sealed ash pit arranged therein, a fuel support arranged
- 10 within the combustion chamber substantially wholly upon one side of the ash pit and having one end thereof projecting across the open top of the ash pit for a slight distance for providing a protecting member, a wind box disposed under the fuel support and having one side thereof serving as a portion of one wall of the ash pit, and a perforated pipe disposed under the protecting member in proximity to the outer wall of the wind box to supply water thereto and to the ash pit.
- 15 2. In a furnace of the character described, a shell having therein a combustion chamber, a fuel support therein having air passages extending therethrough, an open top 25 water sealed ash pit arranged at one side of the fuel support and adapted to receive consumed and partially consumed fuel therein, a wind box disposed under the fuel support and adapted to supply air to the 30 air passages of the fuel support, one side of said wind box forming a portion of one side of the ash pit, and means to discharge water upon the said exposed side of the wind box for externally cooling it and to supply 35 water to form the seal for the ash pit.

In testimony whereof I affix my signature in presence of two witnesses.

LEWIS METESSER.
